UNITED STATES PATENT OFFICE.

JOHN W. CROUSER, OF NEW YORK, N. Y.

FOUNTAIN-PEN-FILLER CONTROL.

1,181,744.

Specification of Letters Patent.

Patented May 2, 1916.

Application filed February 5, 1915. Serial No. 6,275.

To all whom it may concern:

Be it known that I, JOHN W. CROUSER, a citizen of the United States, and a resident of the city of New York, borough of Manhattan, in the county and State of New York, have invented a new and Improved Fountain-Pen-Filler Control, of which the following is a full, clear, and exact description.

10 My invention relates to fountain pens provided with an elastic ink reservoir, and has reference more particularly to the means for varying the volume of the elastic reservoir by compressing the same.

15 The object of the invention is to provide a simple, convenient and inexpensive fountain-pen filler control which, when accidentally displaced on the pen, will not cause a variation in the volume of the elastic reservoir and, consequently, eject a part of the ink thereof through the pen.

20 With the above and other objects in view, the nature of which will more fully appear as the description proceeds, the invention 25 consists in the novel construction, combination and arrangement of parts as herein fully described, illustrated and claimed.

25 In the accompanying drawings, forming part of the application, similar characters of 30 reference indicate corresponding parts in all the views, and Figure 1 is a longitudinal section of a fountain pen embodying my invention; Fig. 2 is a side elevation, partly in section, showing the elastic ink eraser 35 compressed by means of my device; Fig. 3 is a perspective view of the plate and lever separated; Fig. 4 is a fragmentary elevation, partly in section, of a modified structure of my plate; and Fig. 5 is a perspective view 40 of the modified structure of the plate as shown in Fig. 4.

45 Referring to the drawings, 4 represents the barrel of the pen which accommodates the elastic reservoir 5 carried by the pen holder 6 connected to the barrel 4 in any suitable way. An elongated plate 7 is located between the elastic reservoir and the interior lateral surface of the barrel. The plate 7 has two longitudinal slits 8, preferably located in the middle part of the plate. The 50 material of the plate between the slits is preferably depressed, as indicated at 8'; while the material to each side of the slits is raised, as indicated at 7'. By depressing and 55 raising the portions 7' and 8', openings 10 are formed in the plate which are engaged

by shoulders of a T-shaped lever 9. The shoulders of the T are maintained against the portions 7' and 8' by the elasticity of the portions 7' and 8'. The portion of the T-shaped lever projecting above the plate 7 is bent laterally from the shoulders of the T and substantially at right angles to the shoulders. The said shoulders of the T-shaped lever 9 are preferably angular, so that the sides of the shoulders will be maintained in contact with the plate 7 under the resiliency of the portions 7' and 8' when said lever is turned on its shoulders as a fulcrum. The barrel 4 is also provided with an opening 11 adapted to register with the depressed portion 8' in the plate 7, and through which opening the lever 9 is adapted to project. The barrel is also provided with an elongated recess 12 on the outer lateral surface thereof adapted to accommodate the lateral portion of the lever 9 when the same is in normal position, as shown in Fig. 1.

To place the lever 9 into operative position the same is turned on its fulcrum to bring the lever 9 from a position substantially parallel to the axis of the barrel (see Fig. 1) to a position substantially perpendicular to the axis of the barrel (see Fig. 2). The resiliency of the portions 7' and 8' 55 maintain said lever automatically in either of said positions, due to the contact of the flat portions of the shoulders of the lever 9 with the plate 7 under the action of the resilient portions of said plate.

By compressing the lever 9 into the barrel the volume of the elastic reservoir 5 is reduced and, consequently, suction will be created when the lever is released and ink will be caused to flow into the reservoir under the action of the atmospheric pressure. The end of the lever 9 is preferably provided with a head 13 facilitating the movement of the lever on its fulcrum formed by the shoulders of the plate 7. It will be noted that if the lever 9 is accidentally displaced from the position shown in Fig. 1 to the position shown in dotted line in the same figure, the volume of the elastic reservoir 5 will not be disturbed and, consequently, the ink within the reservoir will not be forced out through the pen holder as is the case with levers of the first class with their fulcrums intermediate the ends. By providing a T-shaped lever which is bent into the shape of a square and which is fulcrumed on its T shoulders at the plate, I eliminate the use

of a fulcrum in the barrel in the shape of a pin, which necessitates the drilling of the lever and the barrel; thus, my pen is cheaper and of a stronger construction.

5 In Figs. 4 and 5 a modified structure of the plate is shown. In this structure the plate 7" is provided with a resilient member 15 which is secured to the upper face of the plate. This resilient member has an 10 opening 14 through which the stem of the lever 9 is adapted to project. This resilient member 15 receives the resilient portions 7' and 8' of the plate. The said resilient member 15, if desired, can be placed on the under 15 side of the plate which contacts with the elastic reservoir.

From the foregoing description, taken in connection with the accompanying drawings, the advantage of the construction and 20 operation of the device shown will be readily understood by those skilled in the art to which the invention pertains; and while I have described the principle of operation, together with the device which I now consider to be the best embodiment thereof, I 25 desire to have it understood that the device shown is merely illustrative and that such changes may be made as are within the scope of the appended claims.

30 Having thus described my invention, I claim as new and desire to secure by Letters Patent:

1. In a fountain pen, a barrel, an elastic reservoir therein, a plate within the barrel 35 engaging the reservoir, and a lever having a lateral portion engaging the plate and fulcrumed thereon with its lateral portion, said lever projecting through the barrel, said plate being resilient at the point where the 40 lever fulcrums, said lateral portion including means for co-operating with the resilient part of the plate for maintaining the lever in an operative or in inoperative position.

2. In a fountain pen, a barrel, an elastic 45 reservoir therein, a plate within the barrel engaging the reservoir, and a T-shaped lever engaging the plate with its shoulders and projecting with its stem through the barrel, the portions of the plate engaging 50 the shoulders being resilient to maintain said lever in operative or in inoperative position.

3. In a fountain pen, a barrel, an elastic reservoir therein, a plate within the barrel 55 engaging the reservoir, said plate having a pair of longitudinal slits in the middle

thereof, the part of the plate between the slits being depressed while the parts of the plate at the sides of the slits are raised, and a T-shaped lever engaging with its shoulders the raised portions of the plate and projecting with its stem through the barrel, said raised and depressed portions of the plate being resilient, whereby said lever is maintained in operative or in inoperative position.

4. In a fountain pen, a barrel, an elastic reservoir therein, a plate within the barrel engaging the reservoir, said plate having a pair of parallel longitudinal slits, the material of said plate between the slits being depressed and the material of the plate at the sides of the slits being raised, and a T-shaped lever engaging with its shoulders the raised part of the plate, the stem of said lever projecting through the barrel, a portion of said stem being bent laterally, whereby the unbent portion is adapted to engage the depressed portion of the plate when said lever is placed into operative position, the depressed and raised portions of said plate being resilient, whereby said lever is maintained in operative or in inoperative position automatically.

5. In a fountain pen, a barrel, an elastic reservoir therein, a plate within the barrel engaging the reservoir, said plate having a pair of parallel, longitudinal slits, a part of the plate between the slits being depressed and the parts of the plate at the sides of the slits being raised, said raised and depressed parts of the plate being resilient, and a T-shaped lever engaging the raised parts of the plate with the shoulders thereof under the action of the depressed portion, said shoulders forming a fulcrum for said lever on the plate, a portion of the stem of the T-shaped lever being bent laterally at right angles to the shoulder of the lever, said barrel having an opening through which the 100 stem of the lever projects, the shoulders of said lever being angular in shape, whereby the resilient part of the plate engaging the shoulder will maintain said lever in operative or in inoperative position.

In testimony whereof I have signed my name to this specification in the presence of two subscribing witnesses.

JOHN W. CROUSER.
